EIGHT CYLINDER RADIAL MOTOR

Bernard L. Baisden, Los Angeles, Calif.

Application February 28, 1931, Serial No. 519,216
Renewed March 11, 1933

2 Claims. (Cl. 74—14)

The object of this invention is to provide a motor in which a number of cylinders are mounted radially with reference to the shaft, mounting a cam, the pistons operating in the cylinders and having connecting rods rigid with reference to the pistons, and thrust being imparted to a double cam on the driven shaft by means of rollers suitably mounted and interposed between the connecting rods and cam.

10 A further object is to provide, in connection with the foregoing, a plurality of arms or links extending between the connecting rods of the pistons at the points where the rollers are mounted, and to provide stationary guiding means 15 for relieving the connecting rods or piston rods of undue strain.

A further object is to provide a unitary member, on each side, by means of which the guiding operation may be effected.

20 A further object is to provide in this type of engine or motor a predetermined order of operation of elements, as hereinafter disclosed.

A further object is to provide an engine or motor of increased efficiency, the weight of the structure being reduced, compared with the weight of many other engines, and to provide for operation on the minimum quantity of fuel.

With the above and other objects in view, the invention further consists of the following novel features and details of construction, to be hereinafter more fully described, illustrated in the accompanying drawings and pointed out in the appended claims.

In the drawings forming part of the application:

Figure 1 is a view in vertical section, transversely thru the driven shaft.

Figure 2 is a section longitudinally thru two of the cylinders, oppositely located, and thru the intermediate mechanisms including the cam carried centrally by the driven shaft.

Figure 3 is an elevation showing the cam detached.

Figure 4 shows one of the pistons in longitudinal section.

Figure 5 is a fragmentary view showing a portion of the structure constituting a guiding frame with radial slots for directing the movement of the pistons.

50 Figure 6 is a detailed view showing a two part connecting element, with provision for the use of a shim in order to effect slight variation in the length of the complete device.

Figure 7 is a view in section on line 7—7 of 55 Figure 6.

Figure 8 is in section, and shows the mounting of one of the rollers and the cooperation thereof with the cam, a portion of which appears in the lower part in section.

The cylinders are designated by the positions 60 referred to in the description of operation, the numerals 1, 2, 3, 4, 5, 6, 7 and 8 being applied, and these cylinders may be of approximately the usual type including the body portion 10, the flange 11 and the connecting flanges 12, by 65 means of which the cylinders are individually secured to a housing shown at 13.

An exhaust connection for each cylinder is designated 14, an intake connection is shown at 15, and the position of the spark plug is designated 70 16.

Each piston 17 cooperates with the cylinder in which it is mounted, and has formed therewith or longitudinally connected therewith a rod 18 to be considered as a connecting rod, and roller 75 19 pivoted on each rod cooperates with the cam 20 shown in detail in Figure 3, and elsewhere illustrated. This cam is rigid with reference to shaft 21 to be driven, and the positions of the rollers with reference to the cam at a particular 80 time are shown in Figure 1.

In order to guide the pistons and their rods, I provide a plurality of frames 25 including a central annular portion and radially extending portions, the latter being slotted at 26 and the elements 27 cooperating with the slots for the purpose indicated. The laterally extending devices 28, formed with the guiding frames, are connected by means of pins or bolts 29 at the points shown, this connection being with ears or the 90 like formed on the inner portion of the housing.

The ends of the connecting rods or piston rods 18 are pivotally connected by means of the devices of Figures 6 and 7, each comprising elements 33, 33' adjustable regarding length by 95 means of securing devices shown at 34, adapted to retain shims when required. The elements last named are not illustrated in the drawings, but their use in this connection will be readily understood. The rollers are mounted at the 100 points of connection indicated in general by reference character 35 in the several figures.

It will be observed that the engine is of the air cooled type and that no crank shaft is employed, the central cam taking the place of the 105 crank elements and a straight shaft being provided.

Referring to the numerals designating the cylinders, the order of firing the charge is 1, 6, 7, 4, 5, 2, 3, 8. 110

The thrust imparted by the pistons on firing the charge is determined by the cam and the peculiar and novel relation between the piston rods resulting from the use of the connecting rods 30, whereby all of the pistons are connected as one assembly and function in harmony with each other.

In Figure 1, cylinder 1 is ready to fire, cylinder 6 is on compression, in cylinder 7 the charge is beginning to be compressed, cylinders 4 and 5 are receiving fuel, in cylinder 2 the exhaust is taking place, cylinder 3 is on the exhaust stroke, and charge in cylinder 8 has just been fired.

The cam 20 in Figure 1 is being thrust toward the left, under the force of the explosion in cylinder 1, and simultaneously the pistons of cylinders 2, 3, 6, 7 are raised, whereas pistons 4, 5 and 8 move inwardly. Cylinder member 6 is on compression when the charge in cylinder 1 is fired. Cylinder 6 is fired and the pistons are raised, or moved outwardly in cylinders 7, 8, 3, 4, the pistons of cylinders 1, 2, 5 moving inwardly, or to the lower position.

The charge in cylinder No. 3 is next fired and the remaining charges are fired in the order before indicated. Emphasis is placed on the fact that the piston rods are held to direct radial movement, that a true balance is always maintained, and that the arms, such as elements 30 connecting alternate piston rods, are included in two sets of toggle joints, the entire assembly of

moving parts being linked together with a view of efficiency in service and the elimination of non-productive motion, including friction.

Without the use of gearing, the device produces the equivalent of a two to one gear ratio, and upon each revolution of the propeller, the pistons complete four cycles.

What is claimed is:—

1. In an engine, a shaft, a plurality of cylinders and pistons therein, piston rods fixed with reference to the pistons and movable in a path radially of the shaft, being aligned with the longitudinal axes of the cylinders, piston guiding elements and unitary means connecting the inner portions of these elements, said elements including outer laterally extending members, a housing, means connecting adjacent laterally extending members with each other and with the inner wall of the housing, rollers connected with the piston rods, axial elements for the rollers, a cam engaging the rollers and transmitting thrust exerted by the pistons, and strain distributing elements connected with the aforesaid axial elements.

2. An engine structure comprising the elements of claim 1, and combined compression producing elements and strain distributing devices connected with the axial elements of the rollers.
